UNITED STATES PATENT OFFICE

167,309

SOUVENIR TOKEN

Curt Freiberger, Denver, Colo., assignor to the City and County of Denver, a municipal corporation of Colorado

Application November 16, 1949, Serial No. 6,081

Term of patent 7 years

(Cl. D29—23)

To all whom it may concern:

Be it known that I, Curt Freiberger, a citizen of the United States, residing in the city and county of Denver, State of Colorado, have invented a new, original, and ornamental Design for a Souvenir Token, of which the following is a specification, reference being had to the accompanying drawing, forming part hereof.

Fig. 1 is a perspective view of a souvenir token showing my new design; and

Fig. 2 is a side elevational view thereof.

The opposite side is the same as that shown except for the name plate.

The characteristic features of the design reside in those portions shown in full lines on the drawing.

I claim:

The ornamental design for a souvenir token, as shown and described.

CURT FREIBERGER.
